UNITED STATES PATENT OFFICE.

STEFANO CHIARELLO, OF BROOKLYN, NEW YORK.

TELESCOPIC CAR STAKE.

Application filed October 5, 1927. Serial No. 224,098.

This invention relates to improvements in telescopic car stakes, and the primary object of the invention is to provide a device of this kind which is extremely simple and durable in construction as well as capable of being readily extended or collapsed.

Another object is to provide means for effectively preventing the entrance of dirt, rain and snow into the tubular members 10 constituting the stake, when the latter is collapsed and applied to a car having a lateral flange upon the upper edge of the side wall thereof.

A still further object is to provide simple 15 and efficient means for retaining the upper stake sections in extended position and for holding the same against lateral movement or vibration when collapsed.

Other objects will appear as the nature 20 of the invention is better understood, and the same consists in the novel form, combination and arrangement of parts herein-after more fully described, shown in the accompanying drawings and claimed.

25 In the accompanying drawings, wherein like reference characters indicate corresponding parts throughout the several views:

Figure 1 is a fragmentary top plan view 30 showing a portion of the side wall of a railway car equipped with a telescopic stake constructed in accordance with the present invention, the side wall of the car having an outwardly projecting lateral flange at its upper edge;

35 Figure 2 is a side elevational view of the device shown in Figure 1;

Figure 3 is a fragmentary side elevational view, drawn on a smaller scale, and illustrating a plurality of the stakes of Figures 40 1 and 2 applied to the outer side of a rail-way car and arranged in extended condition;

Figure 4 is a view similar to Figure 2 of 45 a stake applied to the inner side of a car having an inwardly extending flange at the upper edge of its side wall, the stake being in extended position;

Figure 5 is a vertical transverse section on line 5—5 of Figure 4;

50 Figure 6 is a vertical section on line 6—6 of Figure 5; and

Figure 7 is a horizontal section on line 7—7 of Figure 4.

Referring more in detail to the drawings, the present stake embodies a tubular lower 55 section 5 of rectangular form in cross-section and adapted to be rigidly secured in a

suitable manner to the side of a railway car, and an upper tubular section 6 also of rectangular cross-section but somewhat narrower than the lower section 5 as clearly 60 shown in Figures 6 and 7 and indicated by dotted lines in Figures 2 and 4.

The lower stake section 5 is provided with a pair of rigid spaced cross bars 7 and 8 in its upper end portion, that are arranged 65 in superimposed vertically aligned relation at one side of the vertical axis of the lower stake section 5. A similar cross bar 9 is provided in the lower end of the stake section 5 at the other side of its vertical axis 70 and formed in the lower end of the stake section 6 is a transverse seat embodying transversely aligned notches 10 in the lower edges of opposing walls of the stake section 6. A further seat is provided in the lower 75 end portion of the stake section 6 embodying opposed notches 11 in opposite walls of said stake section 6 above the notches 10, and these notches 11 lead upwardly from the inner end of a lateral entrance slot 12 provided in the lower end portion of the stake 80 section 6 between the notches 10 and 11.

The stake section 6 is of such a width as to readily pass downwardly into the stake 85 section 5 and sit between the cross bars 7 and 8 and the side wall of the stake section 5 furthest from the latter when the stake section 6 is lowered to collapsed position as shown in Figure 2. When thus lowered, the stake section 6 is effectively held against lateral movement or vibration by reason of the cross bars 7 and 8 engaging a side thereof and by reason of the cross bar 9 engaging in the notches 10. When it is desired to extend the stake, the upper section 6 is lifted 90 until the cross bar 8 is disposed directly beneath the lower end of the stake section 6 and the cross bar 7 is in registry with the entrance slot 12. The stake section 6 is then shifted laterally until the same engages the 95 opposite side wall of the stake section 5 and the cross bars 7 and 8 are vertically registered with the slots 10 and 11. The stake section 6 is then lowered so that the cross bars 7 and 8 are seated in the notches 10 and 100 11, whereupon the upper stake section is effectively supported in its extended or raised position and in a most secure or rigid manner. Obviously, when it is desired to again lower the section 6, it is simply lifted 105 and then shifted laterally so that the cross bars 7 and 8 are disengaged therefrom and

110

the stake section 6 is shifted entirely to one side of the cross bars 7 and 8 and against the opposite side of the stake section 5. The stake section may then be lowered between 5 the cross bars 7 and 8 and the side wall of the section 5 furthest from the latter, at which time the cross bar 9 is again seated in the notches 10.

Vertically slidable on the upper end portion 10 of the upper stake section 6 is a rectangular slide ring 13 to the inner side of which is suitably connected one end of an ordinary load binding chain 14 by means of which the load is effectively bound upon the 15 car when piled above the upper edge of the side wall of the latter with the stake section 6 raised or extended. As the use of these load binding chains is well understood in the art, further disclosure or comment thereon 20 is deemed unnecessary. However, opposite sides of the stake section 6, at the upper end of the latter are formed with upwardly and outwardly tapering stop lugs 15 which limit the upward adjustment of the slide ring 13 25 and prevent it from being accidentally displaced off of the upper end of the stake section 6.

Obviously, the present stake may be designed for attachment to the sides of a flat 30 bottom car, or the lower stake section 5 may be designed to extend through the bottom of a gondola car and for attachment to the side sill —S— of the latter as at —a— so as to act as a stanchion or a brace for the side 35 wall of the car. However, in the form of the invention shown, the lower stake section 5 is simply seated at its lower edge upon the floor 16 of the car body and bolted as at 17 to the side wall 18 of the car body. In the 40 illustration of Figures 1 to 3 inclusive, the side wall 18 of the car body is formed with an outwardly projecting horizontal flange 19 at its upper edge, and the car stakes are disposed at the outer side of the wall 18 with 45 the sections 5 thereof bolted to the wall 18 in vertical alinement with and below vertical cut away portions or openings 20 in the flange 19 so that the stake sections 6 may be readily raised or elevated therethrough. In 50 this instance the flange 19 may be formed with a short upstanding flange 21 about the cut away portion or opening 20 and hinged to the flange 19 at one side of each opening 20 is a cap-like cover 22 adapted to fit over 55 the flange 21 and close the opening 20 for effectively excluding the entrance of dirt, rain and snow into the upper ends of the stake sections when collapsed. Naturally, when the stake sections are to be extended, 60 the covers 22 are swung upwardly and laterally to open position upon their hinges 23 as shown in Figures 3, 4 and 6. The lower stake section 5 preferably consists of a channel-shaped member 24 having out-turned 65 flanges 25 along its free vertical edges, and a

plate member 26 applied to the open side of the member 24 for closing said side thereof and bolted with the flanges 25 to the side wall 18 of the car through the medium of the bolts 17, referred to above. The plate member 26 is disposed flatly against the side wall 18 of the car and is assembled to the member 24 before being bolted to the car, while the cross bars 7, 8 and 9 are riveted in the member 24 at corresponding ends, while their 70 other ends are riveted in the plate member 26 after the latter is applied against the flanges 25. This provides for convenient and economical manufacture and assembly. 75

In order to limit the upward movement of the upper stake section 6 so as to prevent it from being pulled out of the lower stake section 5 to an excessive extent, a suitable spring drum or roller —R— may be mounted in the lower end of stake section 6 upon which is normally wound a flexible member or wire —W—, said wire being anchored at one end to the drum and at its other end to the lower stake section 5, or its cross bar 9 as at —b—. 80

The only difference between the construction of Figures 1 to 3 inclusive and that of Figures 4 to 7 inclusive is that the side wall 18^a of the car body has the flange 19^a thereof projecting inwardly instead of outwardly, 85 and the car stake is bolted to the inner side of the wall 18^a instead of to the outer side thereof. 90

From the foregoing description it is believed that the construction and manner of use as well as the advantages of the present invention will be readily understood and appreciated by those skilled in the art. 100

Minor changes may be made without departing from the spirit and scope of the invention as claimed. 105

What I claim as new is:—

1. A telescopic car stake comprising tubular upper and lower sections, and rigid horizontal cross bars arranged in spaced superposed relation in the upper portion 110 of the lower section at one side of the vertical axis of the latter, said upper section being slidable into and outwardly of the lower section between one side of the latter and said cross bars, and having notches in the lower portion thereof to receive the cross bars when the upper section is raised, shifted laterally and slightly lowered, whereby to support said upper section in elevated position. 115

2. A telescopic car stake comprising tubular upper and lower sections, and rigid horizontal cross bars arranged in spaced superposed relation in the upper portion 125 of the lower section at one side of the vertical axis of the latter, said upper section being slidable into and outwardly of the lower section between one side of the latter and said cross bars, and having notches in 130

the lower portion thereof to receive the cross bars when the upper section is raised, shifted laterally and slightly lowered, whereby to support said upper section in elevated position, one of said notches being in the lower edge of the upper section and another being above said edge, said upper section having a lateral entrance slot from the bottom of the latter notch.

10 3. A telescopic car stake comprising tubular upper and lower sections, and rigid horizontal cross bars arranged in spaced superposed relation in the upper portion of the lower section at one side of the vertical axis of the latter, said upper section being 15 slideable into and outwardly of the lower section between one side of the latter and said cross bars, and having notches in the lower portion thereof to receive the cross bars when the upper section is raised, shifted laterally and slightly lowered, whereby to support said upper section in elevated position, one of said notches being in the lower edge of the upper section and another 20 being above said edge, said upper section having a lateral entrance slot from the bottom of the latter notch, and a further cross bar for seating in the lower notch when the upper section is lowered, said further cross 25 bar being carried by the lower portion of the lower section at the opposite side of its vertical axis.

30 4. A telescopic car stake comprising a lower section having horizontal supporting members arranged in spaced superposed relation, and an upper section slideable into and outwardly of the lower section between one side of the latter and said supporting members, and means on the upper section 35 engageable with said supporting members, when the upper section is elevated and shifted laterally and lowered, to rigidly sustain the upper section in elevated position.

40 5. A telescopic car stake comprising tubular upper and lower sections, and rigid horizontal cross bars arranged in spaced superposed relation in the upper portion of the lower section at one side of the vertical axis of the latter, said upper section being 45 slideable into and outwardly of the lower section between one side of the latter and said cross bars, and having notches in the lower portion thereof to receive the cross bars when the upper section is raised, shifted 50 laterally and slightly lowered, whereby to support said upper section in elevated position.

55 6. A telescopic car stake comprising a lower section embodying a side plate member and a channel-shaped member having outturned flanges adapted to be bolted together and to the side of a car.

60 65 7. A telescopic car stake comprising tubular upper and lower sections, and rigid horizontal cross bars arranged in spaced superposed relation in the upper portion of the lower section at one side of the vertical axis of the latter, said upper section being slideable into and outwardly of the lower section between one side of the latter and said cross bars, and having notches in the lower portion thereof to receive the cross bars 70 when the upper section is raised, shifted laterally and slightly lowered, whereby to support said upper section in elevated position, said lower section embodying a side plate member and channel-shaped member having 75 out-turned flanges adapted to be bolted together and to the side of a car, said cross bars having ends riveted in said plate and channel-shaped members.

80 85 8. The combination with a car body having a side wall provided with a lateral flange at its upper edge, said flange having an opening, of a telescopic car stake including a lower section secured to the side wall beneath the flange and an upper section adapted to be elevated through said opening, and a closure for said opening.

90 95 8. The combination with a car body having a side wall provided with a lateral flange at its upper edge, said flange having an opening, of a telescopic car stake including a lower section secured to the side wall beneath the flange and an upper section adapted to be elevated through said opening, and a closure for said opening, hinged upon said flange, said flange having an upstanding short flange about the opening over which the closure is adapted to fit when closed.

100 105 9. The combination with a car body having a side wall provided with a lateral flange at its upper edge, said flange having an opening, of a telescopic car stake including a lower section secured to the side wall beneath the flange and an upper section adapted to be elevated through said opening, and a closure for said opening, said lower stake section being extended below the floor of the car and secured to the side sill of the latter to form a brace or stanchion for the side wall of the car.

110 In testimony whereof I affix my signature.
STEFANO CHIARELLO.
